UNITED STATES PATENT OFFICE.

WILLIAM SPALCKHAVER, OF NEW YORK, N. Y., ASSIGNOR TO ROBERT HOE,
THEODORE H. MEAD, AND CHARLES W. CARPENTER, OF SAME PLACE.

PRINTING-MACHINE.

SPECIFICATION forming part of Letters Patent No. 616,981, dated January 3, 1899.

Application filed December 21, 1896. Serial No. 616,377. (No model.)

To all whom it may concern:

Be it known that I, WILLIAM SPALCKHAVER, a citizen of the United States, residing at New York, (Brooklyn,) county of Kings, 5 and State of New York, have invented certain new and useful Improvements in Printing-Machines, fully described and represented in the following specification and the accompanying drawings, forming a part of the same.

10 This invention relates to bed and cylinder machines; and the improvements consist in means whereby the mechanisms may be readily adjusted to the manipulation of sheets of varying lengths without the necessity of re-

15 setting the main working parts, thereby adapting it for the speedy making of short runs on different-sized sheets, all of which is particularly hereinafter fully described.

The illustrated embodiment of the invention is represented as follows: Figure 1 is a side elevation of such a machine in which the impression-cylinder C is equipped with means for producing and manipulating sheets of different lengths. Fig. 2 is a plan view of the 20 same. Fig. 3 is a plan view taken on the section-line 3 of Fig. 1. Fig. 4 is a partial end elevation of Fig. 1, looking in the direction of the arrow 4 in Fig. 1. Fig. 5 is an enlarged side elevation of the compound adjustable driving 25 segment-wheel for causing and controlling the paper-feeding movement. Fig. 6 is a plan view thereof. Fig. 7 is a sectional plan thereof on the section-line 7 of Fig. 5. Fig. 8 is an enlarged side elevation of the segment-wheel 30 shown in Fig. 5, but with the adjustable parts of said wheel in a different adjusted position. Fig. 9 is an enlarged sectional elevation on the section-line 9 of Fig. 10. Fig. 10 is an enlarged longitudinal sectional elevation of the 35 same on the section-line 10 of Fig. 9. Fig. 11 is a sectional view on line 11 of Fig. 9. Fig. 12 is an enlarged end elevation of the impression-cylinder C as seen looking at the non-gear end in the position of taking a sheet. Fig. 40 45 13 is an enlarged sectional elevation of the impression-cylinder C similar to Fig. 9, but with the parts in the position reached when the sheet is being delivered. Fig. 14 is a partial side elevation of Fig. 13 as seen looking 50 in the direction of the arrow 14. Fig. 15 is an enlarged end elevation of the impression-cyl-

inder stop mechanism. Fig. 16 is an enlarged sectional plan view of one end of the impression-cylinder as seen on the section-line 16 of Fig. 15. Fig. 17 is a similar view as seen 55 on section-line 17 of Fig. 15. Fig. 18 is a diagrammatic illustration of the means for operating the cutting mechanism.

Arrows point the directions in which the various views are seen.

This printing mechanism in its general characteristics is of ordinary construction and may be of any construction differing from that shown. As shown, the impression-cylinder C rotates in the usual bearings provided 65 in the side frames, and its shaft 10 carries a toothed wheel 20, gearing with the bed-rack 21, by which it is driven.

The traveling bed B is supported in a usual manner, as in ways or on rollers 51, and its 70 reciprocation is produced by mechanism similar to that used in the Wharfdale printing-machine. Its driving-wheel 22, which is engaged with the rack 23 on the under side of the bed B, revolves on a shaft 24, and this 75 shaft also carries on its opposite ends two spur-wheels 6 7, (see Fig. 4,) that gear with short fixed longitudinal racks 25 26, these wheels 6 7 also having flanges 27 28 on their outer faces, which run upon longitudinal rails 80 29 30.

The shaft 24, carrying the large wheel 22 and the smaller ones 6 7, is journaled in the outer arms of a connecting-rod 32, which is reciprocated by means of a crank 31 on the 85 driving-shaft 33, to which rod 32 it is pivoted, as is common in bed motions of this character and known as the "railroad" motion.

By the use of the large and smaller spur-wheels 22 and 6 7 the motion is multiplied, 90 and a short crank movement produces the long reciprocation of the bed. By duplicating the wheel 22 and providing the bed with two corresponding racks greater stability may be given to the movements of the bed; but 95 this might also be attained by making the wheel 22 and rack 23 of sufficiently greater width.

The impression-cylinder C in this illustrated machine is a stop-cylinder driven from 100 the bed-rack, as we have seen. Its stop mechanism is illustrated in Figs. 15, 16, and

17, and consists of means for arresting the same at each revolution. The wheel 20 is free to turn on the shaft 10, except when locked thereto by the dog 8, which engages a 5 recess in its inner periphery. (See Figs. 15 to 17.) This dog is pivoted to the cylinder-head and pressed to this duty by a spring-rod 46, and its locked condition is released by means of an arm 2, that is appropriately 10 engaged by a cam 85, that is rocked on the shaft 10 (see Fig. 17) through a connecting-rod 84, a rock-arm 185 (see Fig. 1) on shaft 86, and a rock-arm 87, that is actuated by a cam 88 on the driving-shaft 33, this cam 88 15 being maintained in its normal position by a spring-arm 99. The outer end of this arm 2 when the latch is withdrawn by the cam to release the wheel 20 from the cylinder is so moved as to seat itself in a jaw 5, that is fixed 20 to the side frame, its engagement with said jaw acting to suspend the movement of the cylinder.

The impression-cylinder C (shown enlarged in Figs. 9 to 14) is, as illustrated, provided 25 with the necessary openings in its shell for the accommodation of the mechanisms and carries a fixed cutting-blade 11, adjustable radially with respect to the periphery of the cylinder and having its cutting edge even 30 therewith or slightly below said periphery. This radial adjustment of the cutting-blade is accomplished by means of slots in the blade and adjusting-screws passing through the same, as shown in Fig. 10, or by any other 35 well-known means. This cylinder is provided (see Figs. 9, 10, 12, and 13) with grippers 12, that coöperate with nipping-arms 19, which grippers work through the openings in the cylinder, as shown. The surface of the cylinder 40 between the openings is unbroken, and therefore forms a single impression-surface, each part of which is ready for instant coöperation with the form after the adjustment of the grippers by the means hereinafter referred to. 45 Said grippers and nipping-arms are supported by a carrier 68, that is capable of swinging on the shaft 10 at one end of the cylinder and which has a member 69, that extends horizontally within the cylinder to support the grip- 50 per-shaft. For the purposes of this invention, as will be understood farther on, this carrier 68 is swung on the shaft 10 into the desired position to adjust the grippers with respect to the size of the sheet being operated upon and 55 held in the adjusted position by means of a suitable screw-clamp 34, which embraces a curved rib 42 and to which it may be fastened at the desired point; but other means for securing it in position may be used. The 60 office of the carrier 68 is to transport bodily the gripper mechanism into and securely hold it in the required position with relation to the cutting-blade 11, or, in other words, secure it the proper distance from the cutting- 65 blade to enable the web to be cut into sheets of the desired length and the gripping mechanism to properly operate upon such sheets.

The grippers are fast upon the shaft 1 and play in suitable openings in the shell of the cylinder, into which openings the nipping- 70 arms 19, that are fast to the member 69, project.

At the end of the gripper-shaft 1 that projects through the carrier 68 is fast a pinion 16, that is engaged on nearly opposite sides 75 by segment-arms 17 and 14. The segment 17 is pivoted to the carrier 68, and its rock-arm is attached to a spring-rod 52, that operates to maintain the grippers closed, and the opposite segment-arm 14, also pivoted to 80 the carrier 68, is provided with a lateral stud 9, that engages a fixed cam 41, contact with which causes the segment 14 to rock, and thus rotate the gripper-shaft at proper times to cause the grippers to be opened at the sheet- 85 releasing point and enable them to close at the sheet-receiving point to properly deliver a printed sheet and take a fresh sheet to be printed no matter what the length of the sheet may be. 90

For coöperation with the cutting-blade 11 a vibrating cutting-blade 13 is provided. Its holder is fast to a rock-shaft 45, that is supported in brackets fast to the side frames. This holder is provided with an arm 37, that 95 is attached to a spring-seated rod 38, by which said blade is normally moved downwardly or into cutting position, and the shaft 45 is provided with a rock-arm 35, (see Fig. 18,) contacting with a cam 98, which is fast on the 100 cylinder-shaft, (see Fig. 10,) by which the vibration of the said cutting-blade is 105 controlled, so that it is vibrated into cutting position, as in Fig. 18, for timely coöperation with the passing blade 11, the latter being adjusted to properly coact therewith in sweeping 110 over its edge.

The paper web is fed forward (see Figs. 1, 2, and 5 to 8) by means of a compound adjustable driving segment-wheel 54 55, one 110 member, 55, of which is fast upon the shaft 10 of the impression-cylinder and the other member, 54, of which is loose on the hub of the wheel 55. The segment 54 is provided with a clamping-screw 57, which extends 115 through a slot 58, with which the segment-wheel 54 is provided concentrically with its periphery, which clamping-screw 57 passes through this slot and enters a tapped hole near the rim of the segment-wheel 55, by 120 which device the two members of the compound segment-wheel are clamped together as one. Each of these segment-wheels 55 54 is provided with an enlarged perimeter of a 125 suitable extent, (illustrated in Fig. 5,) whereby said segment-wheels operate as a cam of like extent when said segment-wheels are clamped together, as in Figs. 5 to 8. This cam or driving surface may be extended, as is illustrated in Fig. 8, by loosening the 130 clamping-screw 57 and swinging the loose segment-wheel 54 the desired distance, which adjusted position may be secured by means of this clamping-screw 57, as shown in that

figure. In connection with this compound cam or paper-feeding segment-wheel there is a broad-faced pulley 56, (see Fig. 6,) one-half of which runs in frictional contact therewith, 5 it being adjusted and held in such frictional contact by means of an adjusting-bolt 43, (see Fig. 1,) attached to the slide, which carries a stud on which the pulley 56 runs freely, and this pulley is made broad enough so that 10 its inner portion may act as a band-pulley to receive and propel a band 61, which, running over a pulley 62 on shaft 186, drives said shaft, which carries a pulley 162, fast thereon. The roll of paper 63 is rotated at a surface 15 speed corresponding with that of the feeding movement imparted by said compound feeding segment-wheel by means of a contact-pulley 65, which constantly rides on said roll and which pulley 65 is driven by means of a 20 driving-band 64, that runs over it and the pulley 162. This pulley 65 is mounted in a swinging frame and rests by gravity in contact with the periphery of said roll of paper 63.

The sheet-delivery apparatus (best seen in 25 Figs. 1, 3, and 13) consists of delivery-tapes 70, that extend from pulleys 71 near the cylinder to and return over pulleys 75. The pulleys 71 are loose on a shaft 92, that is hung in two arms 72 on studs supported by brackets 30 depending from the side frames, each of said arms 72 being provided with a rock-arm 73, having a spring-seated rod 74, that constantly acts to throw forward the shaft 92 and the parts it carries. As the pulleys 71 thus 35 pressed forward would otherwise enter into the cylinder-opening near the cutting-blade 11 when that opening is presented to them, the shaft 92 is provided with bearing-rollers 90, (see Fig. 14,) which bear on the unbroken 40 part of the cylinder, and thus at that time prevents such movement of the pulleys 71 and at all times act to limit the forward position of the pulleys 71 and the tapes 70, carried by them, which are thus held nearly in contact 45 with the lower periphery of the impression-cylinder. This shaft 92 also carries fast friction-rollers 91, which bear on the margins of the sheet and act with the cylinder C to drive the sheet onward to the tapes 70 when the 50 grippers release it, and there is provided a stripping blade or arms 66, projecting sufficiently near the face of the cylinder to act as a means for diverting the sheet from the cylinder and guide the same onto said tapes. 55 These tapes are driven at an appropriate speed by means of driving-bands 79 and 76, extending, respectively, from a pulley 82 on the shaft carrying the pinion 81, which meshes with the driving-wheel 80 on the driving-shaft 33, to a double pulley 77, and from double pulley 77 to a pulley 95.

In order to print a short sheet, the members 54 55 of the compound segment driving-wheel will be adjusted and set in the position shown 60 in Fig. 5—that is to say, they will be adjusted with respect to each other and be locked together with the high parts of each coinciding,

thus constituting one instrumentality. The friction-pulley 56 will have contact with the raised parts of this compound segment driving-wheel for a distance equal to the length of a short sheet, the result being that the feeding action will only be in operation while such contact is had. When it is desired to feed a longer length of paper, the clamping-screw 57 70 is loosened and the member 54 of this compound feeding segment-wheel is shifted until the length of the raised or cam portion of the compound driving segment-wheel 54 55 shall represent the length of sheet desired to be 75 manipulated, and which may then appear as is illustrated in Fig. 8, where the high part of this compound driving segment-wheel is shown as lengthened by such adjustment, which is secured by tightening the clamping-screw. 80

As the normal position of the grippers is that suited to the action upon the shortest sheet, comparing the relation of the grippers to the cutting-blade, Fig. 9, with the adjusted 90 cam-surface in Fig. 5, it will be necessary when that raised cam or driving surface is extended, as in Fig. 8, to separate the grippers a longer distance from the said cutting-blade in order that an appropriate longer length of 95 paper may be carried onward with the cylinder C before the cutting devices operate to sever the sheet length, and this is accomplished by swinging the carrier 68 into appropriate position and there securing the same. 100 The grippers will then operate as before (but at an earlier time) and properly close and seize the sheet at the receiving-point and open and release it at the delivery-point.

In the operation of this machine the web 105 of paper extending from the rolled web 63 over the thin supporting end of the feeding-table 50 and resting motionless thereon will have its end seized by the grippers 12 when they arrive in their rotary travel in position 110 to close upon the same, the high parts of the compound driving segment-wheel 54 55 contacting with the friction-pulley 56, the result being that as the grippers seize the end of the web said friction-wheel 56 will begin to 115 revolve and through the belt 61 and connecting mechanisms appropriately drive the paper-roll 63. The paper will then move onward at the velocity with which the impression-cylinder travels and the paper will be lapped onto 120 the impression-cylinder to be printed. When the predetermined sheet's length has passed onward, the cutting-blade 13 will be vibrated at the appropriate time by the action of the cam 98, so that it will contact with the cutting-blade 11, the web being severed by the coaction of the two blades to form the predetermined length of sheet. The free part of each sheet, or tail end thereof, will be prevented from falling away from the cylinder 130 by means of the curved guards 3, which depend from arms 4. As soon as the web is severed the high part of the compound driving segment-wheel will have passed from con-

tact with the friction driving-pulley 56 and the paper will have ceased to move. When the leading end of this sheet reaches the discharging-point, the grippers will be opened 5 to release it, and the same will be propelled onward by the friction-rollers 91, and thus pass out onto the tapes 70 for delivery in the usual manner, the stripper-blade 66 preventing the sheet from following the surface of 10 the cylinder. It will be understood that at the time the bed is making its return stroke the roll of paper will be motionless and the cylinder will be in a state of rest, caused by the seating of the arm 2 in the stationary jaw 15 5; also, that when the time therefor arrives the cam 85 will be rocked to release the arm 2 and permit the latch or dog 8 to engage the cylinder-wheel 20, and thus cause the paper-feeding cam to timely operate and the grippers and cutting devices to perform their functions. 20

What is claimed is—

1. The combination with a cylinder provided with a cutting-blade and with a grip-
25 per mechanism adjustable to and from said blade, of a cutting-blade external to the cylinder and coöperating with said blade, mechanism for feeding the web to said cylinder and means for suspending the feed of said
30 web when the cutters operate, substantially as described.

2. The combination with a sheet-receiving cylinder or carrier, of a cutting-blade supported thereby, and a blade adjacent to said cylinder and co-operating with said blade, of a gripper mechanism carried by the cylinder and adjustable with respect to the cutting-blade and an adjustable driving mechanism for actuating the web-feeding devices, substantially as described.

3. The combination with a sheet-receiving cylinder provided with a cutting-blade and with a gripper mechanism adjustable to and from said blade and operating to seize the sheet at the cutting-point, of a cutting-blade adjacent to said cylinder co-operating with said blade, and a mechanism for feeding a web to said cylinder and an adjustable means for suspending the feed of said web when the cutters operate, substantially as described.

4. In a printing-machine the combination with the paper-receiving cylinder carrying a cutting-blade operating at a fixed point and provided with a gripper mechanism adjustable to different points with relation to said cutting-blade, of means driven by the rotation of said cylinder and adjustable to feed a length of paper suited to the various adjustments of the grippers, substantially as described.

5. The combination with an impression-cylinder having a single unbroken impression-surface of fixed circumferential length, of a gripper mechanism having a circumferential adjustment with respect to said cylinder, substantially as described.

6. The combination with an impression-cyl-

inder having a single unbroken impression-surface of fixed circumferential length, of a gripper mechanism having a circumferential adjustment with respect to said surface, and a cutting mechanism, substantially as described. 70

7. The combination with an impression-cylinder having a single unbroken impression-surface of fixed circumferential length, of a gripper mechanism having a circumferential adjustment with respect to said surface, and a cutting mechanism having a fixed relation to said impression-surface, substantially as described. 75 80

8. The combination with an impression-cylinder having a single unbroken impression-surface of fixed circumferential length, of a gripper mechanism having a circumferential adjustment with respect to said surface, and a cutting mechanism one member of which is mounted at the end of the impression-surface, substantially as described. 85

9. The combination with an impression-cylinder having a single unbroken impression-surface of fixed circumferential length, of a gripper mechanism having a circumferential adjustment with respect to said surface, a cutting mechanism and a web-feeding mechanism, substantially as described. 95

10. The combination with an impression-cylinder having an impression-surface of fixed circumferential length, of a gripper mechanism having a circumferential adjustment with respect to said cylinder and capacitated to engage the cylinder at any point within the range of adjustment, substantially as described. 100

11. The combination with an impression-cylinder having a single unbroken impression-surface of fixed circumferential length, of a gripper mechanism having a circumferential adjustment with respect to said cylinder and capacitated to engage the cylinder at any point within the range of adjustment, substantially as described. 105 110

12. The combination with an impression-cylinder having an impression-surface of fixed circumferential length, of a gripper mechanism having a circumferential adjustment with respect to said surface and capacitated to engage the cylinder at any point within the range of adjustment, and a cutting mechanism, substantially as described. 115

13. The combination with an impression-cylinder having a single unbroken impression-surface of fixed circumferential length, of a gripper mechanism having a circumferential adjustment with respect to said surface and capacitated to engage the cylinder at any point within the range of adjustment, and a cutting mechanism, substantially as described. 125

14. The combination with an impression-cylinder having an impression-surface of fixed circumferential length, of a gripper mechanism having a circumferential adjustment with respect to said surface and capacitated to engage the cylinder at any point within the

- range of adjustment, and a cutting mechanism, one member of which is mounted at the end of the impression-surface, substantially as described.
- 5 15. The combination with an impression-cylinder having a single unbroken impression-surface of fixed circumferential length, of a gripper mechanism having a circumferential adjustment with respect to said surface and capacitated to engage the cylinder at any point within the range of adjustment, and a cutting mechanism, one member of which is mounted at the end of the impression-surface, substantially as described. 60
- 10 16. The combination with an impression-cylinder having an impression-surface of fixed circumferential length, of a gripper mechanism having a circumferential adjustment with respect to said surface and capacitated to engage the cylinder at any point within the range of adjustment, a cutting mechanism, and a web-feeding mechanism, substantially as described. 65
- 15 17. The combination with an impression-cylinder having a single unbroken impression-surface of fixed circumferential length, of a gripper mechanism having a circumferential adjustment with respect to said surface and capacitated to engage the cylinder at any point within the range of adjustment, a cutting mechanism, and a web-feeding mechanism, substantially as described. 70
- 20 18. The combination with an impression-cylinder having an impression-surface of fixed circumferential length, of a gripper mechanism having a circumferential adjustment with respect to said surface, a cutting mechanism, a web-feeding mechanism including means for suspending the feed of the web when the cutting mechanism operates, substantially as described. 75
- 25 19. The combination with an impression-cylinder having an impression-surface of fixed circumferential length, of a gripper mechanism having a circumferential adjustment with respect to said surface, a cutting mechanism, a web-feeding mechanism including adjustable means for suspending the feed of the web when the cutting mechanism operates, substantially as described. 80
- 30 20. In a printing-machine, the combination with an impression-cylinder of fixed circumferential length, of a gripper mechanism having a circumferential adjustment with respect to said surface, a cutting mechanism 85
- 35 having a fixed relation to said impression-surface, and means driven by the rotation of the cylinder and adjustable to feed a length of paper suited to the various adjustments of the gripper mechanism, substantially as described. 90
- 40 21. The combination with a shaft, of a cylinder carried on said shaft, a gripper mechanism coöperating with the cylinder and carried by the shaft, a transverse cutting mechanism one member of which is supported on the shaft and means whereby a circumferential adjustment is effected between the grippers, and the cylinder and cutting mechanism, substantially as described. 95
- 45 22. The combination with a shaft, of a cylinder carried on said shaft, a gripper mechanism coöperating with the cylinder and carried by the shaft, a transverse cutting mechanism one member of which is supported on the shaft, means whereby a circumferential adjustment is effected between the grippers, and the cylinder and cutting mechanism, and web-feeding means, substantially as described. 100
- 50 23. The combination with a shaft, of a cylinder carried on said shaft, a gripper mechanism coöperating with the cylinder and carried by the shaft, a transverse cutting mechanism one member of which is supported on the shaft, means whereby a circumferential adjustment is effected between the grippers, and the cylinder and cutting mechanism, and adjustable web-feeding means, substantially as described. 105
- 55 24. The combination with a shaft, of a cylinder carried on said shaft, a gripper mechanism coöperating with the cylinder and carried by the shaft, a transverse cutting mechanism one member of which is supported on said shaft, means whereby a circumferential adjustment is effected between the grippers, and the cylinder and cutting mechanism, and web-feeding means driven by the rotation of the cylinder and adjustable to feed a length of paper suited to the adjustments effected between the other mechanisms, substantially as described. 110

In testimony whereof I have hereunto set my hand in the presence of two subscribing witnesses.

WILLIAM SPALCKHAVER.
